UNITED STATES PATENT OFFICE.

MATTHÄUS KLINGLER, OF OBERNDORF, GERMANY.

DOOR CHECK AND CLOSER.

SPECIFICATION forming part of Letters Patent No. 701,054, dated May 27, 1902.

Application filed January 26, 1901. Serial No. 44,876. (No model.)

To all whom it may concern:

Be it known that I, MATTHÄUS KLINGLER, a citizen of the German Empire, residing at Oberndorf-on-the-Neckar, in the Kingdom of 5 Würtemberg, Germany, have invented certain new and useful Improvements in Door Checks and Closers; and I do hereby declare the following to be a full, clear, and exact description of the invention, such as will enable 10 others skilled in the art to which it appertains to make and use the same.

This invention relates to a simple device capable of being mounted on doors, windows, and the like by means of which said doors, 15 windows, and the like may be fixed in a totally or partially opened position or automatically entirely closed, while in the latter case by another simple arrangement a violent slamming to of the door or the like is prevented.

The device essentially consists of a flat spring having two arms, both ends of which have a spring action against one another. One arm of the spring—*i. e.*, the longer one— 25 terminates in a support fixed to the frame of the door, window, or the like, while the other shorter arm terminates in one arm of a bent piece, having its other arm pivotally mounted in the said support, and both arms form at 30 the coinciding part a slot in which a pin, fixed to the door and serving for operating the latter, slides with the movement of the door.

In the accompanying drawings, Figures 1 35 and 2 are front and end elevations, respectively, of the device, conventionally showing its application to a swinging door. Fig. 3 is a plan view indicating different positions of the device in dotted lines. Fig. 4 is a plan 40 view showing the device equipped with a checking attachment. Fig. 4^a is a detail plan view of the checking attachment, and Figs. 5 and 6 are respectively front and end elevations of the device equipped with the 45 checking attachment.

The flat spring consists of two arms *a* and *b*, of unequal length, having at their free ends a mutual spring action, which arms are connected with one another by means of a loop 50 *c*. The end of the longer arm *a* is fitted on a fixed pin *f* on a bracket *d*, while the end of the shorter arm *b* is fitted on one branch *e*²

of a U-shaped lever *e*, the other branch of said lever being pivotally mounted in the said bracket *d*. A pin *g* engages with the loop *c* 55 of the spring, which pin is riveted to a plate *h*, attached to the door *t*. The bracket *d* is preferably fixed to the door-frame *w*.

The device works in the following manner: As the free ends of the two arms *a* and *b* of the spring have a tendency to mutually 60 spring apart, when these ends are compressed the spring-arm *b*, mounted on the branch *e*² of the lever *e*, will tend to move away from the other firmly-mounted end of the arm *a* 65 of the spring—that is to say, it will tend to turn the U-shaped lever *e*. When the branch *e*² is in a straight line with the pin *f* and the branch *e*, as indicated at II in Fig. 3, there is no turning action, but the lever *e* is pressed 70 radially outward by means of the spring-arm *b* and the spring *a* *b* remains stationary in a given position. In this position, which is shown in dotted lines in Fig. 3, the door is held fast by the spring in a half-open position. It 75 is, for instance, assumed in the drawing that the door is standing here approximately at right angles to its closed position—that is to say, half-open. Of course according to the position of the pin *f* and the branch *e*² relatively 80 to one another the door may be opened to a different width. If the door be turned from its half-open position in one of the directions indicated by the arrows to the position marked I or that marked III in Fig. 3, the spring- 85 arm *b* acts on the lever *e* in such a way that this latter is turned to the left or the right, as the case may be, whereupon the spring follows this direction of rotation of the lever and exerts a pressure on the door—that is to 90 say, it closes the door in the position shown in Fig. 3 (I) or fully opens it to the position shown in III, Fig. 3. As is evident, the spring closes or opens the door automatically as soon as it is turned out of its central position 95 in one direction or the other. In the central position (marked II) the door may be said to be on a dead-center, as the spring then presses it in neither direction.

In order that the door when being closed by 100 the pressure of the spring shall not be slammed violently to, the arrangement shown in Figs. 4 to 6 is employed. This consists of a checking device *i*, adjustably mounted

on the bracket *d* by means of a screw-nut *k*, located on the branch *e'* of the lever *e*, which checking device is provided with a slot *s*, Fig. 4^a, at the place where the branch *e'* passes through it. The checking device *i* has two elbow-shaped projections *i'* *i''* on one of its sides, in which projections set-screws *l*, *n*, and *o* are located. The head of one screw *l* bears against an angular projection *d'*, provided on the bracket *d*. The ends of the other screws *n* and *o* bear against the bracket *d*. The checking device has on its under side a tongue *m*, against which when the door is closed the end of the arm *b* of the double spring strikes when swinging in a semicircle. The bearing of the spring-arm *b* has play on the branch *e'* in such a way that on the spring encountering the tongue *m* the spring *b* can give way so far that it slips over the tongue and the branch *e'*—that is to say, the lever *e* turns completely so far that it assumes the position shown in Fig. 3. The impetus accumulated by the closing of the door is checked by the contact of the spring *b* on the tongue *m* of the brake-support and the forcing back of the spring until it can pass the tongue, as the spring by encountering the brake-support has its action on the door momentarily stopped or checked. When the spring *b* has been released, it has just sufficient strength to completely close the door.

As appears from the foregoing, this simple closing device effects almost as completely a quiet closing of the door as the more expensive closing devices at present employed and which are provided with air-pistons and a cylinder.

The closing and fastening device for doors and the like shown in the drawings may be also employed for windows and the like in quite the same manner, with or without the brake device, and thus the closing of the windows may be effected in an automatic and gentle manner.

This improved device in addition to greater simplicity and cheapness also possesses an advantage over the devices at present employed for the same object, in that doors, windows, and the like are held fast equally automatically in half-opened or entirely-opened positions.

Having now particularly described and ascertained the nature of my said invention and in what manner the same is to be performed, I declare that what I claim is—

1. A door-closing device consisting essentially of a spring having divergent arms, one

of which has its free end fitted on a fixed support, and a swinging lever connected with the free end of the other arm of the spring, the 60 said spring having a loose connection with the door.

2. The combination of a supporting-bracket adapted to be secured to a fixed object, a U-shaped lever having one branch pivoted in 65 said bracket, a pin fixedly mounted in said bracket, and a spring loosely connected with the door and having divergent arms, the end of one arm being fitted on the fixed pin and the end of the other arm being fitted on the 70 free branch of the U-shaped lever.

3. The combination of a supporting-bracket adapted to be secured to a fixed object, a lever pivoted in said bracket, a spring adapted to be loosely connected with a swinging object 75 as a door, gate or shutter having divergent arms, one of which has a fixed connection with the bracket and the other of which has its end fitted on the free end of the lever, and a brake or checking device supported on 80 the bracket and projecting into the path of the lever and the spring-arm connected therewith.

4. The combination of a supporting-bracket adapted to be secured to a fixed object, a lever pivoted thereon, a spring adapted to be loosely connected with a swinging object as a door, gate or shutter having divergent arms 85 one of which has a fixed connection with the bracket, and the other of which is fitted 90 on the lever, and a checking device adjustably mounted on the bracket and having a tongue depending into the path of the lever and the spring-arm fitted thereon.

5. The combination of a supporting-bracket 95 adapted to be secured to a fixed object, a lever pivoted thereon, a spring adapted to be loosely connected with a swinging object as a door, gate or shutter having divergent arms one of which has a fixed connection with the 100 bracket and the other of which is attached to the end of the lever, a checking device extending into the path of the lever and the attached spring-arm and provided with projections on its upper side, and set-screws 105 engaging said projections and adapted to secure the checking device on the supporting-bracket.

In testimony whereof I affix my signature in presence of two witnesses.

MATTHÄUS KLINGLER.
